TOY MERRY-GO-ROUND

Bernard J. Assendrup, Seattle, Wash.

Application October 30, 1943, Serial No. 508,284

1 Claim. (Cl. 272—31)

1

My invention relates to amusement devices, and has among its objects and advantages the provision of an improved toy in the nature of a merry-go-round, wherein a revolving platform is mounted on a wagon, in which a drive connects the platform to one axle of the wagon to rotate the platform when the wagon is moved, and in which the platform is provided with movable figures actuated through rotation of the platform.

In the accompanying drawings:

Figure 1 is a side view of the toy.

Figure 2 is a front view.

Figure 3 is a transverse sectional view.

Figure 4 is a plan view of a part of the wagon platform, and

Figure 5 is an end view of the center pole of the merry-go-round with sound producing plates attached thereto.

In the embodiment of the invention selected for illustration, I make use of a toy wagon 10 having a platform 12. Brackets 13 are attached to the bottom face of the platform 12 by screws 14. A rear axle 16 is rotatably journaled in the brackets 13, which axle has wheels 18 mounted thereon. At least one of the wheels 18 is keyed to the axle, as by a pin 20.

Two front wheels 22 are mounted on an axle 24 supported by brackets 26 fixed to a cross beam 28 pivotally connected at 30 with the platform 12. A tongue 32 is pivotally connected at 34 with the beam 28.

A center pole 36 is mounted vertically on the platform 10, as by a square end 38 on the pole pressed into a square opening 40 in the platform. A key pin 42 is passed through the end 38 to restrain the pole from accidental withdrawal. Upon the pole 36 is mounted a merry-go-round 44, which includes a platform 46 and a top plate 48. Four outer posts 50 and four inner posts 52 are fixed to the platform 46 and the plate 48 in upright positions, the posts in each set being spaced ninety degrees apart. A tapered roof 51 is mounted on the plate 48 and has an opening 52 in its apex to loosely receive the pole 36.

An opening 54 in the plate 48 loosely receives the pole 36, and the platform 46 has an opening 56 which also loosely receives the pole, so that the merry-go-round may be rotated about the pole as an axis. A pin 58 is passed through the upper end of the pole 36 and engages the apex of the roof 51 to hold the merry-go-round on the pole. Four wheels or rollers 60 are mounted on

2

the lower face of the platform 46 to roll on the platform 10 and balance the merry-go-round.

A ring 62 lies adjacent the lower face of the platform 46 to serve as a mount for a gear 64. The gear and the ring are fixed to the platform 46 by screws 66 threaded into the lower ends of the inner posts 52. Screws 68 secure the outer posts 50 to the platform 46 and the plate and the upper ends of the inner posts 52 to the plate.

10 A gear 70 is arranged at right angles to and meshes with the gear 64. The gear 70 is fixed to a shaft 72 rotatably supported in bearings 74 attached to the bottom face of the platform 10. A slot 76 is cut in the platform 10 to bring the gear 70 into engagement with the gear 64, which lies above the platform 10. To the shaft 72 is fixed a grooved wheel or pulley 78 for connection with a belt 80 passing around a grooved wheel or pulley 82 fixed to the rear axle 16.

15 Figures 84 are pivotally mounted on horizontal shafts 86 attached to the outer posts 50 and the inner posts 52. Each figure 84 is provided with a wire 88 which passes through a slot 90 in the platform 46. Upon the platform 10 is mounted a plurality of cams 92 arranged to be engaged by the wires 88 when the merry-go-round is rotated to impart movement to the figures 84. The wires 88 are attached to the forward parts of the figures 84 and the latter are so balanced as to press the wires 88 downwardly in engagement with the cams 92.

20 To the post 36 are fixedly attached two metal plates 94, as by screws 96. These plates project in opposite directions from the post 36. Both 25 plates 94 are provided with fingers 98, the fingers on one plate being progressively longer upwardly, while the fingers on the other plate are progressively shorter upwardly. Pins 100 are attached to the inner posts 52 to engage the fingers 98, the fingers on the respective posts engaging different fingers 98 to produce a musical sound.

25 An opening 102 in the platform 10 receives a part of the wheel 78 so that the shaft 72 may lie closely to the platform 10.

30 Without further elaboration, the foregoing will so fully explain my invention, that others may, by applying current knowledge, readily adapt the same for use under various conditions of service.

35 I claim:

30 A toy of the type described, comprising a platform mounted on wheels, an upright post rigidly supported on said platform, a merry-go-round rotatably supported on the post above the platform and spaced therefrom, rocking figures carried by the merry-go-round, means extending

through the base of the merry-go-round and engaging cams on the platform for rocking the figures, and means carried by the base of the merry-go-round between the same and the platform for rotating the merry-go-round and operated by the supporting wheels of the platform.

BERNARD J. ASSENDRUP.
